UNITED STATES PATENT OFFICE.

FRANK BUCHANAN, OF SYRACUSE, NEW YORK.

HEADLIGHT.

1,194,946.

Specification of Letters Patent. Patented Aug. 15, 1916.

Application filed January 23, 1915. Serial No. 4,047.

To all whom it may concern:

Be it known that I, FRANK BUCHANAN, a citizen of the United States, and a resident of Syracuse, in the county of Onondaga and State of New York, have invented 5 a certain new and useful Headlight, of which the following is a specification.

This invention relates to headlights, and has for its object a particularly simple and 10 efficient means for supporting a plurality of lenses; and it consists in the combinations and constructions hereinafter set forth and claimed.

In describing this invention, reference is 15 had to the accompanying drawings, in which like characters designate corresponding parts in all the views.

Figure 1 is a face view of this headlight, the door being shown as swung open. Fig. 20 2 is a sectional view, the door being shown as closed in full lines, and as open in dotted lines. Fig. 3 is an inner face view of the door showing the operation of the retaining ring for the inner lens. Fig. 4 is an enlarged fragmentary view taken on the plane 25 of line A—A, Fig. 1.

This invention comprises, generally, a casing open at its front side, a movable door for the open front side, and a plurality of lenses supported by the door. In 30 addition, the invention preferably includes a particularly simple and efficient means for supporting one lens by means of which it can be removed in order to be replaced by 35 another lens.

1 is the casing which is here shown as cylindrical in general form and as having a peripheral annular flange 2 midway between its front and rear ends, and as having 40 its rear side formed with a central convex portion 3. The flange 2 is for the purpose of engaging the front side of a dash board when the headlight is set into the dash board.

45 4 designates the door as a whole, the door including a body 5, a ring member 6 on the outer side of the body, spacing means 7 projecting from the rear side thereof, a frame element 8 mounted on the spacing means 50 and having a central opening, a ring 9 coacting with the frame element 8, and lenses 10, 11 carried, respectively, by the body 5 and by the frame element 8, the lens 10 being clamped between the ring member

6 and the body 5, and the lens 11 being 55 clamped between the frame element 8 and the ring 9. The body 5 is formed with suitable hinge leaves 12 connected by a hinge pin 13 to complementary hinge leaves 14 on the casing 1, and said body is also 60 provided with outwardly extending lugs 15 having open-ended slots 16 therein which receive pivoted screws 17 provided on the casing 1. The screws 17 thread into members 18 which pivotally support the screws, 65 the members 18 being pivoted to lugs 19 on the casing 1, and being bifurcated and extending on opposite sides of the lugs 19. The heads of the screws 17 bear against the faces of the lugs 15 when the door is closed. 70 The body 5 is formed with an annular groove 20 around its lens-opening; the lens 10 is provided with a marginal flange or bead which is seated in said groove; and the ring member 6 is arranged to hold said 75 margin in the groove, the margin being protected by a suitable wrapper or filler 21. The ring member 6 is held in position by suitable screws 22 and is also formed with a cylindrical shield 23 which extends in 80 front of the lens. The frame element 8 is in the form of a ring having laterally extending lugs 24 which bear upon the outer ends of the spacing means 7, which means are in the form of posts, and the lugs are 85 secured to the posts by screws 24'. The frame element 8 is also formed with an annular face and with a suitable seat or groove 25 for the lens 11. The ring 9 is opposed to the annular face of the frame 90 element 8 and clamps the marginal flange 26 on the lens 11 between the frame element and said ring. Said ring 9 is pivoted to the element 8 on a pivot extending transversely through the ring 9 and into the frame 95 element 8, that is, parallel to the axis of the lens, whereby the ring can be moved on its pivot in a plane parallel to the frame element 8, that is, crosswise of the axis of the lens 11. The ring 9 is held by spring means 100 in its operative position. In the illustrated form of this ring, it is formed with diametrically opposite ears 27, 28 through one of which the pivot extends, and at the other of which the ring is held from opening 105 movement, the spring means being located at said ears 27, 28.

29 is the pivot which consists of a screw

or pin extending through the ear 27 and into one of the lugs 24 of the frame element 8, the pivot being here shown as combined with one of the spring pressed means. Said means includes a cup 30 mounted on the pivot and bearing on the outer face of the ear 27, and a spring 31 in the cup and bearing against the head of the screw and against the bottom of the cup. Preferably, 10 a sleeve 32 surrounds the pin 29 and bears against the head of the pin 29 and against the face of the frame element 8, said sleeve being secured to the ring 9. The cup is also provided with an annular or laterally extending flange 33.

The spring normally presses against the bottom of the cup and hence presses the ear 27 toward the face of the frame element 8. When it is desired to relieve the ring 9 of 20 the pressure, in order that it may be moved about its pivot when the other spring pressed means associated with the ear 28 is operated, the operator presses his thumb on the head of the pin or screw 29 and engages 25 his first and second fingers with the flange 33 so that when the thumb and said fingers are pressed toward each other, the cup 30 will be pulled outwardly away from the ring 9.

30 The ear 28 is formed with an open-ended slot 34 substantially concentric with the pivot 29, which slot receives a pin 35 fixed in a laterally extending lug 36 on the frame element 8, this pin having spring-pressed 35 means associated therewith similar to the parts 30, 31, 32, 33, just described.

The lenses 10, 11 are concavo-convex and are formed on their opposing sides with prismatic zones, the effect of the lens 11 being to gather all the light rays from the lamp and scatter the same over the rear face of the lens 10 which refracts the rays and projects them forwardly in a shaft composed of parallel rays.

45 The lamp 37 is located so that its filament or source of light is at the focal axis of the lens 10, and in order that it may be accurately arranged the lamp socket 38 thereof is adjustable. As here shown, the base of 50 the lamp socket is mounted on a carriage 39 having bearings 40 on opposite sides thereof of which receive guide rods 41 depending from a bracket 42 secured to the rear wall of the casing 1, the bearings 40 being adjustable along the guide rods 41 and having set screws 43 by means of which the carriage 39 is held in its adjusted position.

The rays of light are reflected onto the lens 10 by means of the spherical reflector, 60 44 located in the rear of the lamp with its axis alined with the focal axis of the lens, the focal point of the reflector being the focal point of the lens 11, at which point the lamp or the filament thereof is also located. The reflector 44 is held at its mar-

gin by rings 45, 46 arranged face to face and having at their inner margins diverging flanges 47, 48 arranged to form a V-shape channel, in which the edge of the reflector is located. The rings 45, 46 are supported on posts 49 extending forwardly from the rear wall of the casing 1 and are secured thereto by screws 50 passing through the rings and into the ends of the posts.

This headlight is particularly advantageous in that a change of lenses 11 can be readily made, as it is oftentimes desirable to substitute an amber lens for a white lens. Furthermore, owing to the arrangement of the lens, the lamp and the reflector, a maximum light is obtained.

What I claim is:—

1. A headlight comprising a lens support, and means for detachably securing the lens to the support comprising an element pivoted to the support at one side of the lens and movable in a direction crosswise of the face of the lens and having a latch at a point opposite its pivot, and holding means associated with the support and located in position to receive the latch which is movable into and out of detachable engagement therewith, substantially as and for the purpose set forth.

2. A headlight comprising a casing, a lens, and means for supporting the lens including a frame element having an annular face, a ring opposed to the annular face, the lens having its margin interposed between the ring and the annular face, and the ring being pivoted to the frame element by a pivot extending transversely of the frame element whereby the ring moves about its pivot in a direction parallel to said annular face, and securing means for the ring including a holding part associated with the frame element and a latch associated with the ring, substantially as and for the purpose described.

3. A headlight comprising a casing, a lens, and means for supporting the lens comprising a frame element, a ring opposed to the frame element, the lens having a marginal flange extending between the frame element and the ring, and securing means having a part thereof extending through the ring into the support across the edge of said margin, a part of said securing means being a latch having an open ended slot and another part of said securing means having a pin associated with the support and extending through the slot when the ring is in its operative position, the pin having spring means associated therewith and co-acting with the latch to yieldingly press the ring toward the support, and the spring means being operable to relieve the latch of the tension of the spring means, substantially as and for the purpose specified.

4. A headlight comprising a casing, a

lens, and means supporting the lens comprising a frame element, having an opening in which the lens is mounted, a ring opposed to the frame element, the lens having a marginal flange extending between the frame element and the ring, and spring means acting on the ring to press the same toward the frame element, the spring means including a pin extending transversely through the ring and into the frame element and having a head at its outer end, a cup slidably mounted on the pin and pressing against the ring, and a spring located in the cup and pressing at one end against the head and at its other end against the bottom of the cup, substantially as and for the purpose set forth.

5. A headlight comprising a casing, a lens, and means for supporting the lens comprising a frame element having an opening in which the lens is mounted, a ring opposed to the frame element, the lens having a marginal flange extending between the frame element and the ring, and spring means acting on the ring to press the same toward the frame element, the spring means comprising a pin extending transversely through the ring and into the frame element, the pin having a head at its outer end, a sleeve 20 encircling the pin and abutting against the head at one end and being secured at its other end to the ring, a cup encircling the sleeve and being open at its outer end, and a spring encircling the sleeve within the cup and bearing at its outer end against the head and at its inner end against the bottom of the cup, substantially as and for the purpose described.

6. A headlight comprising a casing, a lens, and means for supporting the lens comprising a frame element having an opening in which the lens is mounted, a ring opposed to the frame element, the lens having a marginal flange extending between the frame element and the ring, and spring means acting on the ring to press the same toward the frame element, the spring means including a pin extending transversely through the ring and into the frame element and having a head at its outer end, a cup mounted on the pin and pressing against the ring, and a spring located in the cup and pressing at one end against the head and at its other end against the bottom of the cup, the cup having a laterally projecting flange at its outer end, substantially as and for the purpose specified.

7. A headlight comprising a casing having an opening in one side, and a door for closing the open side of the casing including a body, a lens supported by the body, the body having projecting spacing means on its rear face, a frame element mounted on said spacing means and having a central opening, a second lens carried by the frame

element in the opening therein, and a ring for coacting with said frame element, the second lens having a flange between the frame element and the ring, substantially as and for the purpose specified.

8. A headlight comprising a casing having an opening in one side, and a door for closing the open side of the casing and including a body, a lens supported by the body, the body having projecting spacing means on its rear face, a frame element mounted on said spacing means and having a central opening, a second lens having a flange between the frame element and the ring, the ring being pivoted to the frame element by a pivot extending transversely through the ring and into the frame element whereby the ring moves laterally relatively to the axis of the lens into and out of operative position, substantially as and for the purpose set forth.

9. In a headlight, a casing open at one side, a door for the open side including a body and a ring shape member mounted on the outer face of the body, spacing means projecting from the rear side of the body, a frame element mounted on the spacing means and having a central opening, a lens supported by the main body of the door and having a portion thereof interposed between the ring shape member and said body, a second lens mounted on the frame element in the opening thereof, and a ring coacting with the frame element to hold the second lens in position, the second lens having a flange extending between the frame element and the ring, and the ring being pivoted to the frame element, substantially as and for the purpose described.

10. In a headlight, a casing, means for supporting a lens comprising a frame element having an opening, a lens mounted in said opening, a ring coacting with the frame element to hold the lens in position, the lens having a flange extending between the ring and the frame element, the ring being pivoted to the frame element by a pivot extending transversely through the ring and into the frame element and having an open-ended slot at a point diametrically opposite its pivot, and arranged substantially concentric with said pivot, and a fixed catch for entering the slot, the pivot and the catch having spring means associated therewith arranged to bear upon the outer face of the ring and press the same toward the frame element and thereby hold the lens in position, substantially as and for the purpose specified.

11. In a headlight, light focusing means, a lamp support including a guide comprising a pair of rods extending in a direction at a right angle to the axis of the light focusing means, a carriage having bearings adjustably mounted on the rods, means for

holding the carriage in its adjusted position along the rods, and a lamp socket supported by the carriage between the rods, substantially as and for the purpose set forth.

5 In testimony whereof, I have hereunto signed my name in the presence of two attesting witnesses, at Syracuse, in the county

of Onondaga, and State of New York, this 28th day of October, 1914.

FRANK BUCHANAN.
